(57) **CLAIM**

The ornamental design for a robotic lawn mower, as shown and described.

DESCRIPTION

FIG. 1 is a perspective view of a robotic lawn mower in accordance with an embodiment of the first present invention;

FIG. 2 is a left view of the robotic lawn mower of FIG. 1; FIG. 3 is a right view of the robotic lawn mower of FIG. 1; FIG. 4 is a front view of the robotic lawn mower of FIG. 1; FIG. 5 is a rear view of the robotic lawn mower of FIG. 1; FIG. 6 is a top view of the robotic lawn mower of FIG. 1; and,

FIG. 7 is a bottom view of the robotic lawn mower of FIG. 1.

The broken lines shown in the drawings are included for the purpose of illustrating the unclaimed portions of a robotic lawn mower. The broken lines form no part of the claimed design.

1 Claim, 7 Drawing Sheets
